UNITED STATES PATENT OFFICE.

PHILIP A. FARRELLY, OF CHICAGO, ILLINOIS, ASSIGNOR TO GREEN & BAUER INC., OF HARTFORD, CONNECTICUT, A CORPORATION OF CONNECTICUT.

X-RAY TUBE.

1,195,157.

Specification of Letters Patent. Patented Aug. 15, 1916.

Application filed October 28, 1915. Serial No. 58,372.

To all whom it may concern:

Be it known that I, PHILIP A. FARRELLY, a citizen of the United States, and a resident of Chicago, in Cook county, State of Illinois, have invented certain new and useful Improvements in X-Ray Tubes, of which the following is a specification.

This invention relates particularly to improvements in the method of mounting the stem which supports the anode.

In the drawings—Figure 1 is a side view of a tube embodying my invention. Fig. 2 is a sectional view on enlarged scale.

Referring to the drawings, *a* denotes the tube, *b* the cathode, *c* the anode, *d* the anode stem, *e* the anode neck of the tube within which the stem is located and secured. Heretofore it has been the practice to punch holes through the anode stem near its outer end (the anode stem being made of a sheet metal rolled up to shape), and to press into these holes the glass of the anode neck of the tube. This left a sharp metallic edge bearing against the glass, with the result that in shipping and handling the tubes it often happened that a sudden jar would

shift the anode stem in the neck, causing it to shear off the small glass projections.

This improvement consists in forming apertures in the anode stem and drawing down the metal to form inturned tubular walls 5, connected with the stem by curved surface 6, and pressing the glass into these tubular extensions. This provides a bearing surface of substantial area between the glass projections and the stem, and to a very great extent obviates any danger of breakage of the glass when the stems have a tendency to shift longitudinally due to a sudden jar or shock.

I claim as my invention:

In an X-ray tube, an anode stem apertured near its outer end and provided at the apertures with inturned tubular walls, and projections from the material of the anode neck of the tube extending into said apertures and bearing against said tubular walls to secure said stem in place.

PHILIP A. FARRELLY.
